UNITED STATES PATENT OFFICE

WILLIAM H. MINER, OF CHAZY, NEW YORK, ASSIGNOR TO W. H. MINER, INC., OF CHICAGO, ILLINOIS, A CORPORATION OF DELAWARE

CAR CONSTRUCTION

Application filed July 14, 1928. Serial No. 292,892.

This invention relates to improvements in car construction.

One object of the invention is to provide a combined locking and center pin for railway car bolsters, especially designed for use in connection with passenger cars, wherein a substantial locking arrangement is had, the pin presenting a large cross sectional area to minimize the possibility of shearing off or of breaking under tension strains to maintain connection between the truck and body bolsters under all conditions.

Another object of the invention is to provide a locking pin having a fixed head at one end and a detachable head at the other end, together with means for preventing detachment of the last named head.

A still further object of the invention is to provide a locking pin of the character indicated, having a fixed head at one end and a detachable nut member at the other end, wherein means is provided for locking the nut to the pin against rotation.

Other and further objects of the invention will more clearly appear from the description and claims hereinafter following.

In the drawing, forming a part of this specification, Figure 1 is a vertical, longitudinal sectional view through the body and truck bolsters of a railway car, illustrating my improvements in connection therewith. Figure 2 is a top plan view of my improved locking pin and Figure 3 is a bottom plan view of the same. And Figure 4 is a transverse, vertical sectional view, corresponding substantially to the line 4-4 of Figure 1.

In said drawing, 10 indicates a portion of the body bolster of a railway car and 11 a portion of the truck bolster thereof. The truck bolster is provided with the usual center bearing plate 13, having a seat 14 in the top thereof, receiving a cooperating depending bearing section 15 of the body bolster. As shown, the truck bolster bearing plate 13 is also provided with an upstanding central boss 16 which engages within a pocket 17 at the bottom of the body bolster. The truck and body bolsters are provided with the usual aligned center pin receiving openings 18-18 and each bolster is provided with a head receiving

pocket 19 to accommodate one of the heads of the center pin.

My improved combined locking and center pin comprises a locking pin member proper A, a detachable screw-threaded cap B, and a securing member C.

My improved locking pin member A has the shank thereof of circular cross section so as to fit within the circular pin receiving openings 18 of the body and truck bolsters. As shown, the shank is provided with an integral head member 20 at the bottom end thereof, and has the upper end thereof screw-threaded, as indicated at 22. The head 20 is of such a size as to be accommodated within the pocket 19 of the truck bolster and have shouldered engagement with the top wall of said pocket to prevent removal of the pin in an upward direction. The head 20 of the pin is provided with an eye member 21, with which a tool may be engaged in removing the pin and placing the same in position.

The detachable screw-threaded cap B is in the form of a hollow cylindrical member, having the annular wall thereof interiorly screw-threaded, as indicated at 23. The cap member B forms, in effect, a detachable head for the upper end of the pin and fits within the pocket 19 of the body bolster and has shouldered engagement with the bottom wall thereof, to prevent removal of the pin in a downward direction.

The screw cap member B is also provided with an upstanding eye 24, similar to the eye 21 of the head 20, by which the same may be manipulated. As shown in Figure 4, the eye member has the upper section thereof transversely slotted, as indicated at 25, to accommodate a portion of the securing member C. At the opposite sides, the screw threads 22 of the pin are cut away to provide vertical slots 26-26 which also cooperate with the securing member. The top wall of the detachable screw cap B is also provided with a pair of openings 27-27 and the threads of the cap are slotted in alignment therewith, the openings and slots of the cap being adapted to be aligned with the slots 26 of the pin, to cooperate with the securing member C.

The securing member C is in the form of a

100

U-shaped clip, having a horizontal top section 28 and downwardly extending arms 29—29. When the screw cap B is secured to the upper end of the pin by engaging the threads 23 of the cap with the threads 22 of the pin, and the slots 26 of the pin have been brought into alignment with the openings 27 and the slots of the cap, the securing member C is attached by inserting the arms 29 thereof through the openings 27 of the cap into the slots of the cap and the slots 26 of the pin and seating the section 28 within the slot 25, the arms 29—29 forming key members cooperating with the slots. As will be evident, the cap B is thus locked to the pin against relative rotation and accidental removal of the cap is prevented. The arms of the securing member C are of such a thickness as to snugly fit the openings 27 of the cap and the slots 26 of the pin, so that when the securing member has been driven home the same will be held in position by frictional contact. The securing member is preferably made of spring steel and the arms thereof are so designed that they will be spread apart slightly when the securing member is detached, whereby the spreading tendency of the same aids in holding the securing member in place when applied.

Although in the present instance the locking pin has been shown as provided with the detachable head at the upper end, it is obvious that the same may be so arranged that the detachable head is located at the bottom end thereof. In the present instance, the pin 30 is assembled with the body and truck bolsters by inserting the same through the opening 18 of the truck bolster so that the head 20 will cooperate with the top wall of the pocket 19 of said bolster. After the pin proper has 35 thus been placed in position, the screw-threaded cap B is engaged with the upper screw-threaded end of the pin and locked by the securing member C, as hereinbefore pointed out. When the pin has thus been assembled with 40 the body and truck bolsters, the bolsters are effectively locked against relative separation, thereby preventing telescoping of the cars in case of collision or other accident. As hereinbefore pointed out, the locking pin may be 45 inserted from the top through the body bolster in certain instances, the detachable screw cap being in that case accommodated within the pocket 19 of the truck bolster.

While I have herein shown and described 50 what I consider the preferred manner of carrying out my invention, the same is merely illustrative and I contemplate all changes and modifications which come within the scope of the claims appended hereto.

55 I claim:

1. In car construction, the combination with body and truck bolsters having aligned center pin receiving openings, each bolster being provided with a shoulder adjacent its opening; of a center pin having a fixed head

at one end, engaging one of said shoulders; a detachable head at the other end of said pin, engaging the shoulder of the other bolster; interengaging means on said pin and detachable head for securing the head to the pin 70 upon relative rotation of said head and pin; and key acting means extending lengthwise of the pin for locking said head against rotation with respect to the pin, to prevent disengagement of said detachable head. 75

2. In car construction, the combination with body and truck bolsters having aligned center pin receiving openings; of a center pin connecting said bolsters, said center pin having a fixed head at one end, having shouldered engagement with one of said bolsters, to hold said pin against endwise removal in one direction; a detachable head at the other end of the pin, having screw-threaded engagement therewith, said head having shouldered engagement with the other bolster to hold said pin against endwise removal in a reverse direction; and key acting means extending lengthwise of the pin and having shouldered engagement with the head and pin for locking the detachable head against rotation with respect to the pin. 90

3. In car construction, the combination with body and truck bolsters having aligned center pin receiving openings and head receiving pockets adjacent said openings respectively; of a pin extending through the openings of said bolsters, said pin at one end having a fixed head having shouldered engagement with one of said bolsters to hold the pin against endwise removal in one direction, said head being seated in the pocket adjacent said bolster; detachable head means at the other end of the pin, cooperating with the other bolster, for holding the pin against endwise removal in a reverse direction, said detachable means having screw-threaded connection with the pin and being seated in the pocket adjacent the last named bolster; and a locking element having shouldered engagement with the pin and said detachable means, to lock the same against relative rotation, said locking element being insertible and removable through the open end of said last named pocket. 110

4. In car construction the combination with body and truck bolsters having aligned center pin receiving openings; of a pin for connecting the body and truck bolsters, said pin having shouldered engagement with one of said bolsters to prevent removal of the pin endwise in one direction; a detachable member at the end of the pin, having shouldered engagement with the other bolster, to hold the pin against endwise removal in a reverse direction, said member and pin having shoulders interengaging upon relative rotation of said member and pin to prevent removal of said member, said member having a locking element receiving opening and said pin 120

having a locking element receiving slot; and a locking element having shouldered engagement with the walls of said opening and slot to hold said member and pin against relative rotation when said shoulders are interengaged.

5. In car construction, the combination with body and truck bolsters having aligned center pin receiving openings; of a locking pin extending through said aligned openings, having shouldered engagement with one of the said bolsters to prevent endwise removal of the pin in one direction, said pin being threaded at the other end; a screw-threaded cap engaged with the threaded section of the pin, having shouldered engagement with the other bolster, to hold said pin against endwise removal in a reverse direction; and a locking element extending through said cap lengthwise of the pin and having shouldered engagement with the latter to lock said cap against rotation with respect to the pin.

In witness that I claim the foregoing I have hereunto subscribed my name this 11th day of July, 1928.

25 WILLIAM H. MINER.
